DESIGN FOR A SEPARABLE CIGARETTE HOLDER

Rocco J. Naddeo, Brooklyn, N. Y.

Application September 1, 1943, Serial No. 111,035

Term of patent 14 years

To all whom it may concern:

Be it known that I, Rocco J. Naddeo, a citizen of the United States, residing at Brooklyn, in the county of Kings and State of New York, have invented a new, original, and ornamental Design for a Separable Cigarette Holder, of which the following is a specification, reference being had to the accompanying drawing, forming a part thereof.

Referring to the drawing:

Fig. 1 is a view in perspective of the separable cigarette holder showing my new design;

Fig. 2 is a plan view of the device shown in Fig. 1; and

Fig. 3 is a cross sectional plan view of the said design.

I claim:

The ornamental design for a separable cigarette holder, substantially as shown.

ROCCO J. NADDEO.
